(22) Filed: **Apr. 11, 2011**

(57) **CLAIM**

(51) **LOC (9) Cl.** 22-05

The ornamental design for a fishing line bite indicator, as shown and described.

(52) **U.S. Cl.** **D22/134**

DESCRIPTION

(58) **Field of Classification Search** D22/134-136,
D22/138-139, 199; 43/43.1, 15-17, 17.5,
43/25, 44.87

FIG. 1 is a side perspective view of a preferred embodiment of the fishing line bite indicator of the present invention showing the Applicant's new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof; and,
FIG. 7 is a bottom plan view thereof.

See application file for complete search history.
